UNITED STATES PATENT OFFICE.

NAPOLEON ST. PETER, OF FAIRFIELD, MAINE.

KNOCKDOWN CONTAINER.

1,334,186.

Specification of Letters Patent. Patented Mar. 16, 1920.

Application filed November 17, 1919. Serial No. 338,452.

To all whom it may concern:

Be it known that I, NAPOLEON ST. PETER, a citizen of the United States, residing at Fairfield, in the county of Somerset and State of Maine, have invented new and useful Improvements in Knockdown Containers, of which the following is a specification.

The object of my present sole invention is the provision of a simple, durable and easily manipulated knockdown container which may be in the form of an imperforate barrel, a ventilated barrel or a pail, either imperforate or ventilated.

To the attainment of the foregoing, the invention consists in the improvement as hereinafter described and definitely claimed.

I have elected to show my knockdown container in the form of an imperforate barrel, and in the drawings, accompanying and forming part hereof:

Figure 1 is a side elevation of my novel container complete, as it appears when filled and ready for shipment.

Fig. 2 is a plan of the upper end of the same.

Fig. 3 is a diametrical section.

Fig. 4 is a plan view of the body and hoops of the container, as the same appear when reduced to a flat state for return shipment.

Fig. 5 is a section on the line 5—5 of Fig. 4, to show the tongue and groove joints between the staves of the body.

Fig. 6 is a transverse section through one of the hoops, and illustrating the permanent connection of the same to the staves of the body.

Fig. 7 is a horizontal section taken through the lapped end portions of one of the hoops, and showing the means for connecting said portions together and to the adjacent stave.

Similar numerals of reference designate corresponding parts in all of the views of the drawings.

The body of my novel container includes a number of staves 1, of wood, fiber or other appropriate material, and metallic hoops 2 at the ends of the staves, the outer edges of the hoops being approximately flush with the ends of the staves. The staves are provided with tongues 3 and complementary grooves 4, with the result that joints are broken between the longitudinal edges of the staves so as to prevent leakage at such

points, and yet the body is susceptible of being reduced to a flat state for return shipment, as shown in Figs. 4 and 5. Each of the hoops 2 is permanently connected to each stave, preferably through the medium of rivets 5, and each hoop has lapped end portions 6 in which are apertures 7 in registration with each other and also in registration with an aperture 8 in the adjacent stave. Extending through the said apertures 7 and 8 are cotter pins 9, the ends of which are designed to be bent against the inner side of the body, so as to strongly hold the staves and the hoops in circular formation. When, however, it is desired to knock down the body, the cotter pins may be expeditiously and easily withdrawn, whereupon the body as a whole will be reduced to a flat state, as shown in Fig. 4.

At their inner sides and ends the hoops 2 are rabbeted, as indicated by 10, to form recesses for the reception of removable heads 11, of wood, fiber or other appropriate material; the said recesses being of such depth that the heads may rest flush with the ends of the staves.

In addition to the elements described, my novel knockdown container comprises cap rings 12, formed by preference of sheet-metal and angular in cross-section, and with an exterior bead 13 at the junction of their vertical and horizontal portions. In the vertical portion of each cap ring 12, is an aperture 14, designed to rest in registration with an aperture 15 in the complementary hoop 2; said apertures being for the reception of a nail 16 through the medium of which the cap ring is held against casual displacement. The vertical portion of each cap ring 12 is also provided with a notch 17 which is designed to receive the adjacent cotter pin 9, and in so doing is adapted to facilitate the placing of the aperture 14 in registration with the aperture 15.

In the practical use of my novel container, the body and the hoops are manipulated into circular formation, and with the end portions of the hoops in lapped relation, and the cotter pins are placed and secured in position, after which the bottom head is placed in the lower end of the body, and the bottom ring 12 is placed on said lower end and is fastened by its complementary nail 16. The material to be shipped is then placed in the body, after which the top head

and the top ring are positioned, and the top ring is secured through the medium of its complementary nail 16.

When it is desired to gain access to the interior of the container, the top nail 16 is withdrawn and the top ring 12 is removed, when the top head may manifestly be readily lifted from the body.

When after the procedure just described, 10 it is desired to knock down the container, it is simply necessary to remove the bottom ring 12 and the cotter pins 9 of the hoops 2, when, as will be readily appreciated, the body may be reduced to a flat state so as 15 to be returned with the heads and rings in a package of small compass.

It will be apparent from the foregoing that notwithstanding the capacity of function ascribed to my novel container, the same 20 is simple and practical in construction, and is well adapted to withstand the usage to which containers of corresponding character are ordinarily subjected. It will also be apparent that the container does not require 25 expensive machinery for its manufacture.

Having described my invention, what I claim and desire to secure by Letters-Patent, is:

1. In a knockdown container, staves having tongues and grooves and also having recesses in the inner sides of their ends, hoops permanently connected to the outer sides of the staves adjacent to the ends thereof and having lapped portions with apertures in 30 registration with each other and with apertures in the adjacent stave, cotter pins detachably connecting the said lapped end portions of the hoops together and to said stave, heads removably arranged within the 35 ends of the staves, and cap rings of angular form in cross-section having notches in 40

their vertically disposed portions to receive said cotter pins and also having apertures designed to be registered with apertures in the hoops to receive fastening nails. 45

2. In a knockdown container, the combination of staves, a hoop permanently connected to the staves and having lapped portions in which are apertures in registration with each other and with an aperture in the 50 adjacent stave; said hoop also having an aperture for the reception of a fastening nail, a cap ring, of angular form in cross-section, arranged on the end of the body formed by the staves and having a notch in 55 its vertical portion, a head interposed between the horizontal portion of the cap ring and abutments in the staves, and a cotter pin occupying the notch in the cap ring and extending through and connecting the 60 lapped portions of the hoop and the adjacent stave; said cap ring also having in its vertical portion an aperture in registration with the last-named aperture in the 65 hoop, and a fastening nail removably arranged in said registered apertures of the hoop and ring.

3. The combination in a knockdown container, of staves arranged edge to edge, exterior end hoops permanently connected to 70 the staves, and arranged with their outer edges flush with the ends of the staves; each of said hoops having lapped portions detachably connected together in lapped relation, heads removably seated in the end 75 portions of the staves, and cap rings of angular form in cross-section, arranged over the heads, stave ends and hoops and detachably connected thereto.

In testimony whereof I affix my signature. so

NAPOLÉON ST. PETER.
